(57) **CLAIM**

The ornamental design for a ring, as shown and described.

DESCRIPTION

FIG. 1 is a top perspective view of the ring;
FIG. 2 is a bottom perspective view of the ring thereof;
FIG. 3 is a front view of the ring thereof, the back view of the ring is identical to the front view;
FIG. 4 is a right side view of the ring thereof, the left side view of the ring is identical to the right side view;
FIG. 5 is a top view of the ring thereof; and,
FIG. 6 is a bottom view of the ring thereof.
The broken lines showing of the inner side of the ring and the polishing shape of the small stones, is for the purpose of illustrating portions of the ring and form no part of the claimed design.

1 Claim, 5 Drawing Sheets
